UNITED STATES PATENT OFFICE.

JAMES B. KINTZING, OF HANOVER, PENNSYLVANIA.

SHUTTLE-BAR MECHANISM.

Application filed May 21, 1925. Serial No. 31,920.

This invention relates to shuttle bar mechanism of looms and particularly to looms of the type for making wire cloth. The primary purpose of the present invention is to provide a latch mechanism for a wire cloth loom, which mechanism will have a long period of life. Other and further objects of the present invention relate to the specific details of the mechanism as described and as recited in the claims.

In the drawings:

Figure 1 is an elevation partly in section of the preferred form of my invention as applied to a wire loom.

Figure 2 is a top plan view of the end of the bar.

Figure 3 is a bottom plan view.

For many years there has been great trouble had with the shuttle retaining latches of wire looms, these latches often wearing out in a week or less. By means of the present invention, the latch is given a considerable longevity. In fact, I have found that latches made in accordance with the present disclosure will continue in constant use for more than a year.

In the drawings the usual hollow square shuttle bar is numbered 10 and carries at its end the customary shuttle guide 11 of standard construction. The bar has two small openings therein 12 and 13 respectively, the first for the vertical arm of the latch 15, and the second, which is nearer the free end of the bar, receives the catch or hook end of the latch. At the far end a casting 16, having a central orifice 17 to receive loosely the rod 18, is pinned to the shuttle bar or otherwise secured to it in a permanent fashion.

The bottom block 20 is preferably a hollow rectangular bearing block fitting snugly within the shuttle bar against both the bottom thereof and the sides. This bottom block is permanently fastened to the bar, preferably by means of the pin 21, which also serves as a pivot for the latch 15, which is of such width as to form a relatively snug fit with the sides of the central opening in the bottom block. It will be noted from the drawings that while the bottom block is in firm engagement with the bottom of the shuttle bar, the rounded end of the latch clears the bottom by a small amount to insure freedom of movement of the latch.

A top block 25 rides on the top of the bottom block and has an opening 27 with beveled rounded surfaces 28 and 29 to engage the

latch to raise and lower it respectively about its pivot 21. The rear end of the top block is preferably extended to substantially the full size of the bore of the shuttle bar and is tapped centrally to receive the rod 18, which is threaded at this end and carries a lock nut 30 to insure exact positioning of the top block with respect to the latch.

The rod 18 carries a collar 32 pinned to it as at 33. A helical spring 35 is confined between the sleeve 36 of the casting 16 and the collar 32 and by its action constantly urges the top block forward to bring the rounded cam-like surface 29 into engagement with the latch to maintain it in depressed or shuttle-holding position. At its free end the rod 18 is threaded as at 40, and on this end is screwed a spool 41 between the ends of which is received the arms of a fork 42 forming the upper end of a pawl lever pivoted as at 44 to the casting 16 and having a pawl end 45, which, at the appropriate time of each stroke, engages the camming surface 46 of a block 47 secured in fixed position with respect to the frame of the loom. By virtue of the threaded engagement of the spool 41 and rod 18, the latch may be made to operate at an extremely definite point in the cycle, and when such position is found by test the spool 41 is locked on the rod 18 by means of the lock nut 50.

The operation of the device is not materially different from the old type of latch. The pawl 45 hits the cam 46 causing the fork 42 to move to the left as shown in Figure 1 and compressing the spring 35 and bringing the cam surface 28 of the top block into engagement with the latch to raise its point to free the shuttle. The similar but opposite shuttle bar now seizes the shuttle and carries it to the other end of the stroke. As the shuttle bar moves in the opposite direction the pawl 45 rides down the cam surface 46 and as soon as it is free the spring 35 restores the latch to down or locking position, in which position it is resiliently held by the spring 35 which yields, however, when the point of the shuttle is received in the end of the shuttle bar.

What I claim is:

1. In combination a hollow shuttle bar, a bottom block secured therein, a latch, a pin passing thru the shuttle bar, the bottom block and the latch to pivot the latch and to hold the bottom block in position, a top block slidably mounted within said shuttle bar in

operative engagement with said latch to raise and lower same, and means for moving said top block to operate the latch.

2. In a shuttle bar mechanism for looms, 5 a hollow tubing shuttle bar, a bottom block secured within said bar to strengthen same, a latch pivoted to said bottom block, a top block slidably mounted on said bottom block and having an opening therein through which 10 said latch passes, a rod secured to said top block and lying within said shuttle bar, resilient means for holding said rod in position to lower said latch into shuttle-holding position, and means located outside of said 15 shuttle bar for moving said rod against said resilient means to raise said latch and free the shuttle.

3. In a wire loom, a hollow shuttle bar, a hollow rectangular bottom block, a shuttle-holding latch, a single pin securing said bottom block rigidly within said shuttle bar and pivoting said latch, a top block lying entirely within said shuttle bar and having an opening therein through which said latch passes 20 in constantly snug engagement, resilient and adjustable means secured to said top block to hold said latch depressed in shuttle-holding position, and means carried in part by the frame of the loom and in part by the shuttle 25 bar for reciprocating said top block with respect to the bottom block to elevate the latch and free the shuttle.

4. In a wire loom hollow shuttle mechanism, a shuttle bar, a reinforcing element located within said bar, a latch pivoted within 35 said shuttle bar to said reinforcing element, and a member sliding upon said element and holding same out of contact with the bottom wall of the hollow bar, and having a plurality of latch engaging surfaces.

5. In a loom, a shuttle bar, a latch, a member directly engaging the latch to raise and lower the latch, and a single means for pivotally supporting the latch and also holding the latch-engaging member out of contact 45 with the walls of the shuttle bar.

6. In a loom, a hollow shuttle bar, a pivoted latch, means for raising and lowering the latch, and additional means for holding the latch raising and lowering means out 50 of contact with the shuttle bar.

7. In a device of the character described, a piece of tubing, a member pivoted within the tubing, a reenforcing element engaging the tubing snugly on opposite sides, and a pin 55 extending thru the tubing and the reenforcing element, serving as a fixed pivot for the member and as positioning means for the reenforcing element, said reenforcing element strengthening the tubing and also serving 60 to keep the pin from bending while being riveted.

In testimony whereof I affix my signature:
JAMES B. KINTZING.
